Application September 1, 1949, Serial No. 4,809

Term of patent 14 years

(Cl. D57—1)

To all whom it may concern:

Be it known that we, Hans Hofer, George Alto, and Robert Dix, respectively, citizens of the United States of America, residing at Chicago, Prospect Heights, and Chicago, respectively, all in the county of Cook and State of Illinois, respectively, have invented a new, original, and ornamental Design for Field Glasses, of which the following is a specification, reference being had to the accompanying drawing, forming a part thereof, wherein:

Fig. 1 is a front perspective view of field glasses, the temples in a folded condition, showing our new design; and

Fig. 2 is a rear perspective view with the temples partially folded.

We claim:

The ornamental design for field glasses, as shown and described.

HANS HOFER.
GEORGE ALTO.
ROBERT DIX.
